CLAIM

The ornamental design for a decorative element for sunglasses, as shown and described.

DESCRIPTION

FIG. 1 is a front perspective view of decorative element for sunglasses showing my new design;

FIG. 2 is a left side view of the sunglasses shown in FIG. 1;

FIG. 3 is a right side view of the sunglasses shown in FIG. 1;

FIG. 4 is a top view of the sunglasses shown in FIG. 1;

FIG. 5 is a bottom view of the sunglasses shown in FIG. 1;

FIG. 6 is a front view of the sunglasses shown in FIG. 1; and,

FIG. 7 is a rear view of the sunglasses shown in FIG. 1.

The broken line showing of the sunglasses frame, portions of the arms, rivets, screws, and hinges is for illustrative purposes only and forms no part of the claimed design.
